UNITED STATES PATENT OFFICE.

JOHN H. MARTINDALE, OF LAKEWOOD, OHIO, ASSIGNOR OF ONE-HALF TO EDWARD G. GILBERT, OF LAKEWOOD, OHIO.

GAS-BURNER.

1,048,716.

Specification of Letters Patent.

Patented Dec. 31, 1912.

Application filed February 19, 1912. Serial No. 678,620.

To all whom it may concern:

Be it known that I, JOHN H. MARTINDALE, a citizen of the United States, residing at Lakewood, in the county of Cuyahoga and 5 State of Ohio, have invented certain new and useful Improvements in Gas-Burners, of which the following is a specification.

My invention relates to a gas burner, and the invention comprises the construction and 10 arrangement of parts substantially as hereinafter described, and more particularly pointed out in the claims.

The object of the invention is embodied in the means substantially as herein shown, 15 whereby a perfect mixture of air and gas and perfect combustion can be maintained at one point while separate supply of the air and gas and control thereof is at a distant point.

20 The device is particularly designed to mix the air and gas in a uniform and thorough manner and in proportionate predetermined quantities with unvarying certainty, forcing both the air and gas into the mixer and 25 burner under fixed pressures and under control of separate valves, which, however, are to be jointly operative.

In the accompanying drawings, Figure 1 is 30 a plan view of a set of my improved devices connected by pipes to an air and gas-distributing manifold. Fig. 2 is a sectional view, on a larger scale, of a single mixer and burner with the manifold and connecting pipes and 35 valves, the pipes being broken to bring the parts into close relations. Fig. 3 is a sectional view of one of the valves which are in duplicate but of different sizes.

40 My invention is of especial value for brick kilns using gas as a fuel and wherein the gas burners are bricked in or covered or otherwise inaccessibly located and the supply of air and gas and the control thereof necessarily placed at a distant point, say fifty feet, more or less, away from the 45 burners. The combined burners and mixers 2 may be of any number and are variously placed in the kiln, Fig. 1 showing an arbitrary arrangement of the burners to convey this idea and to illustrate that necessity 50 often compels the use of different lengths of air pipes 3 and gas pipes 3' to connect the burner with a source of air and gas supply, which is through a manifold 4 having a central division wall 5 to provide separate 55 air and gas chambers 6 and 7 respectively

therein. Intake of air and gas into said chamber is by pipes 8 and 9 at the ends of manifold 4. Burner 2 is preferably constructed with an offset 10 to receive pipe 3, the longer portion of mixer-body 11 of the 60 device having a pipe 12 extending therethrough from end to end and projecting a suitable distance at its outer end to provide a discharge or burner nipple 14 for the mixed air and gas, and specifically speaking, the nipple 14 is the burner proper of the device and may obviously be of other form than of the blow-pipe type as shown. Pipe 12 is closed at its ends to the interior of the mixer-body 11, but otherwise open 70 thereto through a series of small perforations 15 which are located at equal distances apart spirally around the pipe within mixer-body 11. This spiral arrangement of openings is deemed important to obtain a thorough and uniform mixing of the air and gas. Thus, it is well understood that it is a difficult matter to thoroughly mix air and 75 gas in absolutely fixed proportions and uniformly for protracted operations and under 80 changing conditions, particularly when the flow and pressure thereof is controlled from a distant point. However, by having openings 15 spirally arranged, the air will pass into the line of gas at a series of radial 85 points successively located one in advance of each other, whereby the air will, in a sense, streak along with the gas and be thoroughly commingled therewith and uniformly distributed therethrough by the time 90 the full length of the pipe covered by said openings is traversed by the gas. This distance may be approximately a foot for a three-fourths inch gas pipe, and the desired result is further induced by definitely 95 fixing the proportions of air and gas to be mixed. This is accomplished in the present instance by a plug 16 having an opening 17 of the requisite diameter centrally therethrough, and which plug 16 is interposed 100 between pipe 12 and pipe 3' within boss 18 on mixer-body 11. The number of openings 15 in pipe 12 is more or less dependent upon the size of opening 17 in plug 16 and to the richness of the gas, and in practice 105 the right amount of air to that of gas is obtained by analyzing the gas and then fixing the number of air openings to be used so as to obtain the proper mixture.

In the nature of things, the amount of 110

air used must exceed the amount of gas and for this reason pipe 3 is much larger than pipe 3', and the valves 18' and 19 for the air and gas pipes 3 and 3', respectively, 5 are also of a size and character to proportionately control the flow of each. Moreover, as fixed and predetermined portions of air and gas are taken care of by the burners it is desirable to control the flow 10 of air and gas simultaneously and in the same proportionate degree. This I accomplish by uniting the respective plugs of the two valves 18' and 19' by a sleeve 20 which 15 compels common rotation when the upper valve is manipulated by a key. Each air and gas valve-plug is therefore also provided with two or more cross-passages 20' and 21 of different diameters, whereby the flow of air and gas may be positively regulated in different degree by a full opening of either one or the other of passage 20 and 21, said passages being angularly-related to admit of one being open while the other remains closed. The plug openings 20 in valve 19 are proportionately smaller than the openings in the plug of valve 18'. Each burner and mixer 2 has two pipes and two valves as described, with the valves 25 preferably located adjacent to the manifold 4 where any one set or all of the valves may be turned on or off at will, the manifold 4 being located in any desired and convenient place, although generally distant 30 from the burners. The air and gas is forced to the burners under pressure; and 35 from ~~to~~ eight ounces pressure is generally

sufficient for all purposes. The air pressure may slightly exceed that of the gas, or be approximately equal thereto to assure a free and full discharge of the perfect combustible mixture at the mouth of the nipple 40 14. With this device I do not have to depend upon the uncertainties of a stack for a draft and supply of air, and the air may be taken into the manifold from an outside source where the air is pure and fresh 45 and with consequent better results at the burner.

What I claim is:

1. A burner and mixer comprising a hollow body having an offset and an air supply pipe leading thereto, a gas-supply pipe extending through said body and projected therefrom at one end and having a series of air-intake openings longitudinally thereof, and a removable plug for said gas pipe having a gas-intake opening therethrough. 50

2. A burner and mixer comprising a hollow body having separate air and gas pipes leading thereto, a pipe extending through 55 said body having a series of spirally arranged openings and projected from said body at one end and connected with said gas pipe at the other end and provided with a reduced gas passage for intake of gas. 60

In testimony whereof I affix my signature in presence of two witnesses.

JOHN H. MARTINDALE.
